(57) **CLAIM**

The ornamental design for a front door for an automobile, as shown and described.

DESCRIPTION

FIG. 1 is a front perspective view of a front door for an automobile showing our new design;

FIG. 2 is a rear perspective view thereof;

FIG. 3 is a front view thereof;

FIG. 4 is a rear view thereof;

FIG. 5 is a right side elevation view thereof;

FIG. 6 is a left side elevation view thereof;

FIG. 7 is a top plan view thereof; and,

FIG. 8 is a bottom view thereof.

The present application claims priority to Japanese Design Registration Application No. JPD2012-017850, filed Jul. 27, 2012.

Our design includes a mirror image of the embodiment depicted.
